James Holden.

UNITED STATES PATENT OFFICE.

JAMES HOLDEN, OF PHILADELPHIA, PENNSYLVANIA.

COAL-SCUTTLE.

Specification forming part of Letters Patent No. 57,137, dated August 14, 1866.

To all whom it may concern:

Be it known that I, JAMES HOLDEN, of the city and county of Philadelphia, and State of Pennsylvania, have invented a new and Improved Coal-Scuttle; and I do hereby declare the following is a full and exact description thereof, reference being had to the accompanying drawings, and to the letters of reference marked thereon.

The nature of my invention consists in making a coal-scuttle of a certain form, of wood, in combination with a protecting-case of metal or sheet-iron to preserve it from fire.

To enable others skilled in the art to make and use my invention, I will proceed to describe its construction and operation.

Figure 1 is a perspective view. Fig. 2 is an elevation of the front end.

Similar letters in each refer to the same parts.

The body of the scuttle is made of wood, and is composed of two flat sides, a' a^2 , and two flat ends, a a^3 , and a flat bottom, a^4 . These are secured together by screws, nails, or dove-

tailed, or other ways well known to carpenters, and form a scuttle shaped as shown in Fig. 1.

The end a widens at the top and the end a^3 narrows toward the top, forming the spout, from which the coal is poured. The bottom a^4 is narrower where it joins a^3 than at the end which joins a .

The upper and front part of the scuttle at B is incased in sheet-iron or metal either screwed or riveted onto the wood to protect it from fire. The inside is also lined with a similar protection, B', Fig. 1. This does not extend quite so far down as the outside covering. C is the handle.

What I claim as my invention, and desire to secure by Letters Patent, is this:

As a new article of manufacture, a coal-scuttle made of flat wooden sides shaped as described, in combination with the sheet-iron casing B B', substantially as described.

JAMES HOLDEN.
